UNITED STATES PATENT OFFICE

ARTHUR STEINNER-GÖLTL, OF VIENNA, AUSTRIA

DEVICE FOR GRINDING RAZOR BLADES

Application filed May 1, 1931, Serial No. 534,248, and in Austria December 10, 1930.

Most of the known grinding and stropping apparatuses for razor blades require a comparatively long manual operation, in order to fulfill their purpose and can only be employed for a certain shape and type of razor blades, mostly double-edged flat blades.

This invention relates to a razor blade grinding and stropping apparatus, which is actuated by a single impetus, and automatically effects an accurate grinding, stropping, polishing and magnetizing of the blade, without any further manipulation on the part of the user. The apparatus also possesses the great advantage, that any type and shape of razor blades, for example single, double, triple, quadruple and multiple edged blades, besides hollow ground blades, can be ground, stropped, polished and magnetized in the same manner, without any alteration whatever being necessary.

The fundamental feature of the invention consists in that a paramagnetic spindle is rotated by the magnetic force of attraction contained therein, actuates a paramagnetic frame with blade fitted thereon, and positively grinds, strops, polishes and magnetizes, the likewise magnetically attracted blade edge by the relative shifting occurring between the spindle head and the blade edge.

Several embodiments of the invention are illustrated by way of example in the accompanying drawings in which:

Fig. 1 shows in top plan view a form of construction of the apparatus for hand drive.

Fig. 2 is a vertical section of Fig. 1.

Fig. 3 is a part vertical section of Fig. 1 on a larger scale.

Fig. 4 shows a blade carrier with blade mounted thereon in top plan view and in longitudinal section.

Fig. 5 shows a second form of construction in top plan view.

Fig. 6 is a part side elevation of Fig. 5.

Fig. 7 shows a special construction of the grinding element in vertical section,

Figs. 8 to 11 show three forms of construction of blade carriers in top plan view and in longitudinal section.

A paramagnetic spindle 2 projects upwardly from a lid (Figs. 2, 3 and 6) of a box 1 forming a guide surface 1' and is rotated by hand or by clockwork or by electric drive. The projecting end 3 of the spindle 2 forms a flat cone, the outer surface of which is inclined in correspondence with the bevel of the cutting edge of the blade to be ground. A frame 4 of magnetic material is placed on the guide surface 1'. The frame 4 is provided with a longitudinal bridge 6, which carries at suitable distances apart pins 6' for holding the razor blade 5. Figs. 4 and 8 show a frame 4 for double-edged blades, Fig. 9 shows a frame for triple-edged blades and Fig. 10 a frame for quadruple-edged blades. For holding hollow ground blades the frame 4 is shaped as illustrated in Fig. 11. The frame 4 is placed against the cylindrical portion of the projecting end of the spindle 3 and held in position by the magnetic attraction of the spindle. The edge of the blade 5 to be sharpened, projecting beyond the upper edge of the frame 4, is positively brought to bear on the conical spindle head, where it is also magnetically held.

By turning the spindle 3 and owing to the magnetic force of attraction the outer side (Figs. 1, 2 and 3) or the inner side (Figs. 5 and 6) of the frame 4 is moved along the spindle. The blade 5 placed on the frame 4 is positively shifted in the direction of the movement of the frame 4, the blade edge, being held uniformly tight, slides over the conical spindle head and is ground or stropped, polished and magnetized.

The invention is based on two movements:

1. The slight relative shifting or moving in like direction for stropping or polishing of sharp or comparatively sharp blades. During this operation the frame 4, as shown in Figs. 1, 2 and 3, moves with its outer edge against the spindle. The blade is carried by a frame 4 of magnetic material, corresponding in shape to, but smaller than the blade, said frame bearing with its outer surface against the spindle 2, its outer sur-

face being shifted along the spindle by the rotation of this latter, so that the movement of the blade edge is in the same direction as the direction of rotation of the spindle 5 and consequently a slight relative shifting occurs. The relative shifting results from the difference in speed between the travel of the contacting radius R of the frame 4 (Fig. 3) and the contacting radius r of the 10 blade edge and also from the retardation of the movement of the blade caused by the frictional resistance between the frame and the guide surface 1'. The spindle 2 and the blade edge move in the same direction. 15 2. Maximum relative shifting or movement in opposite directions for grinding strongly worn blades. In this instance the blade is surrounded by the magnetic frame 4 (Figs. 5 and 8), which bears with its inner 20 surface against the spindle 2 and is shifted along the spindle when this latter is rotated. Thus, the blade moves in the opposite direction to the direction of rotation of the spindle so that maximum relative shifting occurs. 25 These two movement phenomena are indicated by arrows in the accompanying drawings.

In order to render it possible, to sharpen even very blunt blades, a cap 7 is placed 30 on the conical head of the spindle 2 (Fig. 7), the conical cover wall 8 of this cap consisting of a grindstone or the like. Also in this instance the blade edge is held on the grindstone by the magnetic attraction of the 35 spindle.

The advantages of the invention consisting in that, contrary to most known grinding devices which must mostly be actuated by hand by turning, drawing or brushing 40 up and down and consequently require time and patience, the present apparatus is operated by a single impetus that is in the apparatus for hand drive by a short single operation, in the apparatus driven by clockwork by winding, and in the apparatus driven electrically by switching in the source 45 of current, and the grinding is effected automatically by the turning of the spindle.

A further advantage consists in that, 50 merely by altering the shape of the frame 4, any shape or type of razor blade can be ground, stropped, polished and magnetized, without it being necessary to alter the apparatus proper. Thus, as already mentioned, not only double-edged blades (Figs. 1 and 5), triple-edged blades (Fig. 10), but also multiple-edged as well as hollow ground blades (Fig. 11) can be ground by means of frames adapted to the shape of the blade. 55

60 Further, in the apparatus according to the invention the microscopically apparent bundle-like frayed out fringes of the blade are laid in the cutting plane by the gliding on the rotating flattened spindle head and stabilized by the magnetism absorbed. More-

over, owing to the automatic acting and to the constant grinding pressure of the edge on the magnetic spindle head, a uniform precision of grinding is obtained, and the blade itself becomes magnetized. 70

I claim:

1. An apparatus for grinding, stropping, polishing and magnetizing razor blades, comprising in combination a casing, a vertical spindle of magnetic material in and projecting from the upper surface of said casing having a grinding surface on its upper end face, means in said casing for rotating said spindle, and a removable carrier for the blade made of paramagnetic material adapted to be placed loosely on the upper surface of said casing and owing to the magnetic attraction between said spindle and said carrier to bear against the cylindrical portion of said spindle and be displaced by the rotation of said spindle to feed the edge of the blade along said grinding surface. 80

2. An apparatus for grinding, stropping, polishing and magnetizing razor blades, comprising in combination a casing, a vertical spindle of magnetic material in and projecting from the upper surface of said casing having a grinding surface on its upper end face, means in said casing for rotating said spindle, and a removable carrier for the blade in the form of a frame made of paramagnetic material in the shape of but smaller than the blade, adapted to be placed loosely on the upper surface of said casing and owing to the magnetic attraction between said spindle and said carrier to bear against the cylindrical portion of said spindle and be displaced by the rotation of said spindle to feed the edge of the blade along said grinding surface. 90

3. An apparatus for grinding, stropping,

polishing and magnetizing razor blades, comprising in combination a casing, a vertical spindle of magnetic material in and projecting from the upper surface of said casing having a grinding surface on its upper end face, means in said casing for rotating said spindle, and a removable carrier for the blade in the form of a frame made of paramagnetic material in the shape of but larger than and consequently extending on all sides around said blade adapted to be placed loosely on the upper surface of said casing and owing to the magnetic attraction between said spindle and said carrier to bear with its inner surface against the cylindrical portion of said spindle and be displaced by the rotation of said spindle to feed the edge of the blade along said grinding surface, in the opposite direction to the direction of rotation of said spindle. 110

4. An apparatus for grinding, stropping, polishing and magnetizing razor blades, 120

comprising in combination a casing, a vertical spindle of magnetic material in and projecting from the upper surface of said casing having a metal cap with inserted 5 grindstone adapted to be placed on the upper end of said spindle to form a grinding surface, means in said casing for rotating said spindle, and a removable carrier for the blade made of paramagnetic material 10 adapted to be placed loosely on the upper surface of said casing and owing to the magnetic attraction between said spindle and said carrier to bear against the cylindrical portion of said spindle and be displaced by the rotation of said spindle to feed the edge of the blade along said grinding surface. 15

In testimony whereof I affix my signature.
